UNITED STATES PATENT OFFICE.

ARTHUR L. FISH, OF SAN FRANCISCO, CALIFORNIA.

STEAM-TRAP.

SPECIFICATION forming part of Letters Patent No. 269,656, dated December 26, 1882.

Application filed October 19, 1882. (No model.)

To all whom it may concern:

Be it known that I, ARTHUR L. FISH, a citizen of the United States, residing at San Francisco, in the county of San Francisco and State 5 of California, have invented new and useful Improvements in Steam-Traps, of which the following is a specification.

This invention relates to devices for emptying steam-traps of the water of condensation; 10 and it consists in the combination, with the trap-body having an inlet-pipe, of a float having an open mouth at its top, a hollow valve-stem, and a hollow valve-chamber having ports, said stem and chamber being connected with 15 the open-mouthed float for receiving the surplus water from the float and discharging it through the valve-stem, the construction and arrangement being such that when the water reaches the proper level in the trap-body it 20 overflows into the float and causes it to sink by gravity, whereby the valve is opened and the water permitted to escape from the float, so that when the float is emptied it rises to an 25 upper or normal position, thereby closing the valve.

This invention is illustrated in the accompanying drawings, in which Figure 1 represents a vertical cross-section. Fig. 2 is a horizontal section. Fig. 3 is a vertical cross-section on the line $x x$, Fig. 1.

Similar letters indicate corresponding parts.

The letter A designates the trap-body; B, the float; C, the float-arm; D, the valve-stem, and E the valve-chamber.

The trap-body A is made of any usual or suitable form, it being provided with an inlet-pipe, F, at the top, and the float, together with the valve, is inclosed in such body. The float is made of cast-iron or other suitable material, 35 with an open mouth, or in form of an open-mouthed vessel, and the arm C projects laterally therefrom. This float-arm is hollow, and is connected to the valve-chamber E on the outer side of the latter, it being open at both 40 ends. The valve-chamber E is annular in shape, and is fitted on the stem D in a suitable manner to rock or oscillate thereon, while both the stem and the chamber are provided with 45 ports g or g' of approximately similar size and shape. The valve-stem D extends through the bottom of the trap-body or through either of its sides or ends, and it is open at the outer

end, where it discharges, it being closed at the inner end.

The motion of the valve-chamber E on the 55 stem is regulated by a stop, h , which also serves to regulate the extreme positions of the float B, and, assuming that the float is in an upper position, when the water of condensation admitted to the trap-body reaches the proper 60 level it overflows into the float and causes the latter to sink by gravity. When the float reaches its lowest position the valve-ports $g g'$ register with each other, they being suitably arranged for this purpose, and the water flow- 65 ing from the float through its hollow arm into the valve-chamber is permitted to escape by way of the valve-stem. When, however, the float has been emptied sufficiently to regain 70 its buoyancy, it rises to an upper position, in which the valve-ports are brought away from each other and the valve is closed.

The stop h consists of a pin projecting from the valve-stem D, and working in a slot, h' , formed in a hub concomitant to the valve-chamber. In order to afford a substantial support to the float, the arm C is connected to it at a point above the bottom, and for the purpose of insuring the discharge of water from the float it is provided with a channel, i , which 80 extends from a point near the bottom of the float to the float-arm, the water being forced up through the channel by the pressure of the steam. The arm, however, can also be connected to the float at or near the bottom, in 85 which case the channel i is omitted.

It will be perceived that by the construction herein described I obtain a balance-valve, which is favorable to the easy and correct working of the parts, and the same condition may 90 be fulfilled by a slight modification in the form of the valve—as, for example, the stem D may be arranged to rotate, leaving the chamber B stationary—and in that event the float is connected to the stem, and the chamber is pro- 95 vided with a means for discharging the water.

In some cases the float-arm may be omitted—that is to say, the body of the float may be enlarged to practically include the arm in its area, and in that event said body is connected 100 directly to the required part of the valve.

What I claim as new, and desire to secure by Letters Patent, is—

1. In a steam-trap, the combination of the

- trap-body A, having an inlet-pipe, F, the float B, having an open mouth at its top for receiving the water in the trap-body when it rises above a proper level, a hollow valve-stem having ports, and a hollow valve-chamber having ports, and connected with the open-mouthed float for receiving the surplus water from the float and discharging it through the valve-stem, substantially as described.
2. In a steam-trap, the combination, with the trap-body A, having an inlet-pipe, F, the fixed hollow valve-stem D, having ports g' , of the hollow valve-chamber E, having ports g , the float B, having an open mouth at its top to receive the

water from the trap-body when it rises above 15 the proper level, and a hollow float-arm, C, having one end opening into the hollow valve-chamber and the other end into the float for conveying the water received in the latter to the valve-chamber and discharging it through 20 the valve-stem, substantially as described.

In testimony whereof I have hereunto set my hand and seal in the presence of two subscribing witnesses.

ARTHUR L. FISH. [L. S.]
